SEALABLE CARTON WITH MULTIPLY BOTTOM

Jack R. Belsinger, Atlanta, Ga., assignor to
Belsinger, Inc., a corporation of Georgia

Application May 6, 1947, Serial No. 746,188

7 Claims. (Cl. 229—23)

1

This invention relates to a carton for containing fruit, bottled goods and other articles.

A feature of the invention is the provision of a carton having a body, a hinged lid, handle structures for lifting and carrying the carton, and sealing arrangements, all presented by the cutting, folding and securing of corrugated board, fiber board, or like stiffly flexible and strong material.

Another feature of the invention is the provision of a carton having a double-bottom thickness and having a body portion formed with a handle structure constituting reinforcement at the upper edge of the body, and provided with a hinged cover which overlaps the reinforcement, and fits in abutment with parts of the body when in closed position, for easy sealing.

A further feature of the invention is the provision of a carton of the aforesaid type, together with stiffening means for strength of the body walls and cover, and providing for a full-height receptacle during packing and an overlap during the closing and sealing.

With these and other features as objects in view, an illustrative form of drawing is shown in the accompanying drawing.

Figure 1 is a perspective view of a closed and sealed carton according to this invention.

Figure 2 is a perspective view of the carton, with the cover opened.

Figure 3 is a lay-out of a first body and cover blank.

Figure 4 is a perspective view showing the blank of Figure 3 folded for assembly.

Figure 5 is a lay-out of a second body blank.

Figure 6 is a perspective view showing the blank of Figure 5 folded ready for assembly.

Figure 7 is a lay-out of a blank for providing an inside stiffening and goods-retaining liner.

Figure 8 is a perspective view of the blank of Figure 7 folded and secured ready for assembly.

Figure 9 is a lay-out of a blank for providing a cover stiffener.

Figure 10 is a perspective view, corresponding to Figure 2, showing the assembled carton with a liner and a cover stiffener, with the cover opened.

Figure 11 is a perspective view of an insert waterproof member.

The basic carton, shown in Figs. 1 and 2, has top and bottom walls 10, 11, front and back walls 12, 13, and the end structures provided each by an end wall 14, the folded hand grips 15, and the overlapping and secured flanges 16, 17, 18. The top wall 10 has integral flanges 19, 20, 21, 22 and

2

tabs 23, 24 which are turned to right-angle positions and secured so that they correspond in cross-section to the free edges of the front wall 12 and to the flanges 16, 17, and abut thereagainst when the carton is closed (Fig. 1). A score line 25 at the plane of the top edges of the flanges 17 provides a hinge about which the cover is swung for opening (Fig. 2) or closing. In closed position, the flanges of the cover overlap the hand grips 15 and provide strong and tight end closures; the back wall is integral; and a sealing tape 28 is applied (Fig. 1) to the front wall 12 and the cover flange in their co-planar and abutting position, for sealing this part of the carton and securing it in closed position.

It will be observed that the top, bottom, front and back walls are smooth outside, so that the filled cartons may be slid easily over a floor or one another, and so that a carton in one stack 10 may be slid out without disturbing contacting cartons in adjacent stacks. These parts, and also the inner faces of the end walls 14, are smooth inside, and thereby avoid damage to sensitive-skinned fruits.

The body and cover of the illustrative carton are formed from two blanks, as shown by the layouts in Figs. 3 and 5.

The blank of Fig. 3 is cut from a single sheet of suitable material such as corrugated board; 30 and has the flange 19, the top or cover wall 10, the flange 20, the rear wall 13, a bottom wall 11a, and the front wall 12 arranged in that order, and separated from one another by the score line 25 for forming the cover hinge and by other score lines 30 parallel to one another and used 35 to facilitate accurate folding. Each of these areas has integral tabs joined therewith across score lines, to provide the tabs 23 on the flange 19; the flanges 21, 22 on the top wall 10; the tabs 24 on the flange 20; the flanges 17 on the back wall 13; the flanges 18 on the bottom wall 11a; and the flanges 16 on the front wall 12. By preference, the front and back walls 12, 13 are 40 of the same height, and the flanges 19, 20 are of the same height; so that the abutment occurs at a common horizontal plane, and the combined height of front wall 12 and flange 19 is equal to the combined height of the rear wall 13 and flange 20.

The blank of Fig. 5 is formed from a single sheet of like material, with parallel edges, and provides in succession the inner fold-flange 15b, the outer fold flange 15a, the end wall 14, the bottom wall 11, the end wall 14, the outer fold-flange 15a, and the inner fold flange 15b. Score

lines 31 are provided to facilitate accurate folding. It is preferred to provide hand holes 14 in the walls 14, at a distance from the adjacent flanges 15^a corresponding to the height of the flanges 15^a in the assembled carton. The width of the sheet, and thus the dimension of the bottom wall 11 from front to back, closely corresponds to the corresponding dimension of the bottom wall 11^a of the blank of Fig. 3, and determines the corresponding inside dimension of the basic carton. The other dimension of the bottom wall 11 determines the inside length of the basic carton; and the corresponding dimension of the bottom wall 11^a is determined by the thickness of the selected material, so that the flanges 17, 18 will fit tightly against the outer faces of the end walls 14.

These blanks can be cut and scored by existing box-factory equipment without difficulty; and can be shipped in the flat to a fruit packer, for example, who employs standard stapling machines to secure the assembly.

The assembly is performed by bending the blanks at the score lines provided, to approximately the forms indicated in Figs. 4 and 6. The hand-grip is formed by turning the inner part 15^b into flat engagement with the outer part 15^a, and then folding the two down flat against the outer face of the corresponding end wall 14, so that (Figs. 2 and 6) the cut edge is located within the triple thickness thus formed, and the folds at the top and bottom of the hand grip portions 14, 15 are smooth. The folded blank of Fig. 6 is then inserted in the blank of Fig. 4, and the parts are stitched together by the stapling machine, into the form shown in Fig. 2. In this operation, the two bottom walls 11^a, 11 lie one on the other, to provide a double bottom thickness, and the front and back walls 12, 13 are fitted against the edges of the bottom wall 11 to give great strength and rigidity to the bottom. The flanges 16, 17 are fitted over and stitched to the end walls 14 and also over and stitched to the folded parts 15^a, 15^b which provide the hand grip 15, to prevent unwinding thereof. The flanges 18 fit closely against the central parts of the end walls 14, at their bottom; and are stitched thereto and to the flanges 16, 17. The stitching of the tabs 23, 24 to the flanges 21, 22, to form the cover, may be accomplished before or after the stitching of the body, as may be more convenient.

The assembled carton (Fig. 2) is easily to load and close: and can be sealed against opening or loss of contents by a single length of gummed tape 28 (Fig. 1). This basic container, with its doubled bottom, smooth internal surfaces, and great end strength, with convenient and natural position of smoothly finished hand grips, is satisfactory for most employments. Sometimes, a particular commodity requires a higher front wall and a greater resistance to damage if dropped upon a corner. This can be attained with the same basic container by introducing a body liner and cover stiffener.

The blank in Fig. 7 is formed from a single sheet of like material, of rectangular shape, having the longer walls 40, 41 and the shorter walls 42, 43, with the securing flange 44; separated by the scored fold lines 45. This is folded and stitched as shown in Fig. 8 to form a sleeve liner of rectangular section; and telescoped into the body of the basic carton, as shown in Fig. 10, and thus provides inner front and back walls of the entire inside height of the carton, with an

over-lap for the flange 19 of the cover, and at the hinge line 25, thereby further strengthening the structure.

The blank in Fig. 9 is formed from a single rectangular sheet of like material, with a central area 50 fitting closely inside the flanges 19, 20, 21, 22 of the cover, and having also the integral flanges 51, 52 separated by scored fold lines 53. This is tucked into the cover (Fig. 10) and stitched into position. It will be noted that the doubled and tripled end flange construction 21-14-13-52 and 22-14-13-53 of the cover fits tightly against the quadrupled thickness provided at the ends of the body by the end walls 14, the flanges 15^a, 15^b, and the liner end walls 52 or 53; so that great rigidity is produced at these points, and extended across the entire cover by the doubling effect of top walls 10, 50. Hence, when closed and sealed, the package is strong; and when open it holds a full load of such products as beans, grapes, currents, etc.

It will be noted that the assembled container is easy to pack, seal, and handle; and that it is easily opened when so desired. Before splitting the sealing tape along the abutment line, undetectable pilfering is difficult or impossible. Also, the double bottom of the basic container, and the doubled walls of the reinforced container, adapt these to uses with products which may give off liquids; and to uses where the package may stand in water, as when placed upon a wet shipping platform: in either case, the liquid may soften and reduce the strength of the layer which it encounters, but does not easily or generally pass to contact with the other layer.

The several parts may be made of boards of different weights or compositions. Thus the blank of Fig. 5 may be of solid fiber board, and that of Fig. 3 of double-faced corrugated board. The board liners of corrugated board may be of sized stock for water repellence.

The same blanks may also be used, in the same way, with the intercalation of a sheet of waterproof stock between the parts, to improve the resistance to internal or external wetting. Thus, a sheet of resin-sized paper, asphalt-coated paper, waxed paper, etc., may be employed. In Fig. 11, such a sheet is shown as folded to provide a thin central field 60 which overlies the total area of the outside bottom part 11^a, and has up-standing walls 61, 62, of height corresponding to that of the flanges 18 and useful to position the sheet during assembly. The specific form of Fig. 11 also has walls 63, 64, and the corners are formed by diagonal folding to provide the wings 65 wherewith a waterproof tray of corresponding wall height is obtained, for inclusion in the container shown in Fig. 10 during its assembly.

It is obvious that the illustrated forms are not restrictive, and that the invention may be employed in many ways within the scope of the appended claims.

I claim:

1. A carton of sheet material comprising double bottom layers, one of the bottom layers having front and back walls connected thereto, the other bottom wall having end walls connected thereto, each end wall being of an integral piece having a triple thickness of the material formed by two successive outward folds essentially parallel to the plane of the bottom and presenting said folds as smooth upper and lower edges and with the cut edge located within the triple thickness, the lower fold being spaced from the bottom to provide a hand grip, the front and rear

walls having flaps fitting against and secured to the end walls, the end walls projecting above the said front and rear walls and the flaps thereof, and a cover having marginal flanges which in closed condition engage the upper edges of the front and rear walls and the flanges thereof and with the end flanges of the cover overlapping the upper portions of the end walls.

2. A carton as in claim 1, in which each end wall has a hand-hole aperture therein with its upper edge substantially at the level of the said lower fold.

3. A carton of sheet material comprising double bottom layers, one of the bottom layers being formed integrally in a first integral structure with a front wall and a rear wall, said front and rear walls having their upper edges below the top of the carton; a rear flange, a cover top, and a front flange also formed integrally with the said one bottom layer, the said first integral structure also having end flaps on the front and rear walls and on the bottom and on the cover top; the other bottom layer being formed integrally with end walls, the upper edge of each end wall being located above said upper edges and formed by a first fold from which a part of the said second integral structure extends downward to a second fold from which a further part thereof extends upwardly between the said first fold and the main part of the end wall, said second fold being located above the bottom to provide a hand grip, said first and second folds providing smooth edges at top and bottom; said flaps on the front and rear walls and bottom being fitted against and outside of the end walls and secured fixedly thereto, the front and rear flanges being secured at the corners of the cover top to said end flaps; said flanges and flaps connected to the cover top being in abutting relation to the upper edges of said front wall and said end flaps in the closed condition of the container, and said flaps of the cover top located outside of and overlapping the parts of the end walls extending above said upper edges of the front and rear walls.

4. A carton as in claim 3, in which a sheet of water-proof material is positioned between the bottom layers.

5. A carton as in claim 3, in which a tray of water-proof material has its bottom positioned between said bottom layers, its upturned ends positioned outside the end walls and within the end flanges of the bottom of said first integral structure, and its upturned front and rear positioned inside the front and rear walls.

6. A carton as in claim 3, in which each end wall has a hand-hole aperture therein with the upper edges of the same substantially at the level of said lower fold, and including a tubular liner having side and end walls fitting closely inside the said side and end walls connected to the bottom layers, the top of said liner extending above the upper edges of the front and rear walls to stiffen the carton at the line of abutment of the front flange upon the front wall and the hinge line at the connection of the rear flange with the rear wall, and extending upwardly substantially to the level of the tops of the end walls and constituting loading walls of substantially the height of the carton interior, said liner presenting closed wall areas opposite each said hand-hole aperture.

7. A carton as in claim 3, and including a reinforcing sheet located inside the cover top and fitting against the same, and having end flanges fitting inside the end flaps, and means effective for securing said reinforcing end flanges to said cover top flanges and said flaps.
